UNITED STATES PATENT OFFICE

GEORGE E. WEBB, OF MILWAUKEE, WISCONSIN, ASSIGNOR TO KOEHRING COMPANY,
OF MILWAUKEE, WISCONSIN, A CORPORATION

BUCKET-DOOR-OPERATING MECHANISM

Original application filed June 15, 1927, Serial No. 199,042. Divided and this application filed August 23, 1928. Serial No. 301,467.

This application is a division of my co-pending application Serial No. 199,042, for boom bucket control mechanism for concrete distributing apparatus, filed June 15th, 1927, 5 and is directed particularly to a novel type of bucket door operating mechanism.

An important object in view is the provision of mechanism of this character which will operate to automatically open and close 10 the bucket door coincident with certain operations of the boom, but wherein the mechanism is dependent for automatic operation only on movement of the bucket along the boom, and is not associated in operation with 15 the cable conventionally employed to cause backward and forward movement of the bucket along the boom. As a result of attaining the end just described, I am able to employ my new bucket door operating mechanism with any type of boom and bucket 20 regardless of what mechanism is availed of for causing movement of the bucket along the boom.

In carrying out my idea somewhat more 25 specifically, I aim to include in the bucket door operating mechanism, a member which is adapted for cooperation with the boom to impart opening and closing actions to the bucket door.

30 A highly important feature is the provision of a member as noted in the preceding paragraph, which is designed to cooperate with the boom upon movement of the bucket in only one direction therealong. This is accomplished in view of the conditions created 35 by conventional operation of a paving machine embodying such a boom and bucket construction wherein a loaded bucket is moved outward along the boom to any desired 40 point without depositing any of its contents on the road bed, but immediately reverse movement is imparted to the bucket, my novel mechanism is operated by the member engaging the boom to open the bucket door 45 whereupon distributing action commences. Upon the bucket reaching the inner end of the boom, certain instrumentalities there located operate to bring into operation the member which cooperates with the boom to cause opening and closing movements of the

bucket door, and in this manner the bucket door is automatically closed so that the bucket is ready to receive a fresh charge of materials.

In a practical embodiment of the invention 55 this member which engages the boom, takes the form of a friction wheel which normally is out of engagement with the boom but which is brought into contact therewith when it is essential to automatically open or 60 close the bucket door through the bucket door operating mechanism.

With these and other objects in view such as those surrounding the provision of instrumentalities automatically bringing the friction wheel in engagement with the boom and the linkage between the friction wheel and the bucket door, as will in part become apparent and in part be hereinafter stated, the invention comprises certain novel constructions, 70 arrangements, and combinations of parts as will be subsequently specified and claimed.

For a full and more complete understanding of the invention, reference may be had 75 to the following description and accompanying drawings, wherein

Figure 1 is a side elevation of the boom and bucket mechanism forming the subject matter of this invention.

Figure 2 is an enlarged view of the bucket and door operating mechanism therefor, the door of the bucket being shown in its open position and as it is about to be tripped for closing just prior to the return of the bucket 85 to the inner end of the boom.

Figure 3 is an enlarged view of the parts of the bucket door operating mechanism including the friction wheel actuator which is disposed in a position assumed at the commencement of the closing movement of the door.

Figure 4 is a detailed perspective view of the rotatable friction wheel used in conjunction with the door operating mechanism, together with a trip pawl included therein and an associated trip lever, and

Figure 5 is a view somewhat similar to Figure 3 showing the position taken when the door is fully closed and the bucket re- 100

turned to its innermost limit of movement on the boom.

While a preferred specific form of the invention is herein set forth, it is to be understood that I am not to be limited to the exact constructions illustrated and described, because various modifications of these details may be provided in putting the invention into practice within the purview of the appended claims.

Throughout the various figures of the drawing and the following description, like reference characters denote corresponding parts.

15 A portion of the mixing drum is shown fragmentarily at A and is rotatably mounted on the framework B of the mixer. A boom C is carried by the mixer and connected therewith by a universal joint connection so that it may be adjusted sidewise as well as vertically. A bucket D is carried by a carriage structure indicated at E which operates along the boom C in a manner clearly described in the copending application previously referred to, of which this case is a division. It is not thought necessary to here go into the detailed description of the driving mechanism for causing movement of the bucket along the boom, as this is fully set forth in the said 20 parent application. It suffices to say that suitable gearing associated with the mixing drum A and framework B causes continuous operation of an endless cable F which has two reaches extending along the other face of the boom, one moving in one direction, and one in the other as is obvious. When it is desired to have the bucket move outward, the carriage E is clutched to one reach of the cable and when the reverse movement is required, 25 the carriage is clutched to the other reach.

40 The bucket D is provided with a swing door 1 suspended from two arms, 2 and 3, and weighted at its upper edge as shown at 4 to provide a counter-balance. The rear edge of 45 the bucket opening for which the door 1 is a closure, has secured thereto a flexible scraper 5 as clearly shown in Figure 2, which functions to remove any material tending to adhere to the surface of the door as it swings to 50 open position, and further insures tight closure when the door swings to closed position. To the arm 2 is affixed an actuating rod 6 having at its point of connection with the arm 2, a cushioning spring 7 within a casing 55 8. These parts constitute an adjustable connection with the arm for insuring proper closing of the door over the bucket opening. Referring to Figure 2, it is noted that the arm 3 is affixed to the bucket D by a pin and slot connection as shown at 3'.

60 The rod 6 is connected at its other end with a crank arm 9 carried at the end of a shaft 10 which is journaled in a bearing 11 on the forward wall of the bucket. A crank arm 12 extends from the central portion of the shaft 10

and is connected by a link in the form of the vertically disposed rod 13 with a crank arm 14 carried by a short shaft 15 journaled in the outer end of a supporting lever 16 which in turn is pivoted at 17 in a hollow head casting 70 of the bucket D. A spring 18 co-operates with the inner end of the lever 16 to yieldably hold the shaft 15 at its so-called elevated position which is determined by an adjustable stop screw 19.

75 Upon the shaft 15 is drivably mounted a friction wheel 20, the periphery of which is provided with interruptions or opposing flats 21 and 22. These flats are formed in the peripheral portion of the wheel which may be comprised of any suitable friction material. Interlocked with the shaft 15 and wheel 20 is a trip lever 23 extending in opposed relation with respect to the crank arm 14. It is the function of this friction wheel 20 to cooperate in contact with the under surface of the boom C as the bucket J travels therealong and by its rotative movement engendered by this engagement to automatically shift the bucket door 1 either to open or closed position as 80 will now be more clearly set forth.

85 Assume that the distributing bucket has deposited its contents upon the surface and under power of the mechanism causing movement of the bucket along the boom, is returning towards the inner end of the boom so as to receive another charge of material. With 90 reference to Figure 2 of the drawings, it will be noted that the trip lever 23 is in its upper vertical position and in its path of movement lies a trip arm 24 carried by the boom and depending therefrom. It is notable that at this time the flat 22 is uppermost and slightly spaced from the boom so that the wheel 20 is out of engagement therewith and stationary. Immediately the trip lever 23 impinges the arm 24, the shaft 15 is rotated in its bearing, causing the true periphery of the wheel 20 to contact with the boom as shown 95 distinctly in Figure 3, marking the initiation of the closing movement of the bucket door, the rotary motion of the wheel being transmitted through the parts 15, 14, 13, 12, 10, 100 and 6 to the door lever 2.

105 When the wheel has rotated so far that the flat 21 reaches the uppermost position, it 110 will then be spaced from the boom, and turning action ceases and the door is in its closed position. This last described rotation of the wheel 20 brings a one-way actuating pawl 25 carried by the wheel 20, into cooperative relation with the boom with which it has, under certain conditions, biting engagement. The bucket is now charged with another load of material and then by means of the driving 115 mechanism for the bucket, it is moved outwardly along the boom until a desired point is reached, whereupon movement of the bucket is reversed. In the outward movement of the bucket, the pawl 25 simply operates along 120 125 130

the surface of the boom without any operative effect, but coincident with reverse of the travel, the pawl 25 bitingly engages the boom, thereby initiating rotation of the wheel 20 sufficiently to bring the true periphery thereof into contact with the boom, and the continuation of the inward travel of the bucket causes further rotation of the wheel 20 which moves the bucket door into open position such as shown in Figure 2, whereby the contents of the bucket are distributed on a road bed. Immediately the bucket door reaches the inner end of the boom, it is automatically closed as previously described.

15 So as to insure proper operation of the bucket door operating mechanism, certain safety instrumentalities are provided which will now be described. Pivotedly mounted on the head of the bucket D adjacent the 20 wheel 20 is a safety friction stop 26 which permits free movement of the wheel 20 in one direction but which functions to prevent any reverse of such movement which might possibly allow the wheel 20 to accidentally 25 operate reversely to the desired direction, as will be clearly understood.

Inasmuch as the inward movement of the bucket not only deposits prepared concrete on a road bed but also distributes the same, 30 I have provided for a variable opening of the bucket door. To this end the crank 9 and its connection with the rod 6 are formed with a series of apertures 27. The number provided in the illustrated construction will 35 permit of three different degrees of the opening of the door such as shown in full and dotted line positions of Figure 2 of the drawing.

The door 1 has the movement in the plane 40 of its body or that of the opening of the bucket which closes, also as it floats, so to speak, into and from closing positions there is caused slight movement lateral to such plane. This insures tight closing especially 45 when the latter movement is obtained by the linkage mounting of the door and the greater length of the arm or link 3 as compared with that of the arm or link 2.

Having thus described my invention, what 50 I claim as new and desire to secure by Letters Patent of the United States, is:—

1. In combination, a boom, a bucket, a carriage therefor to traverse said boom, means to move the bucket outwardly and inwardly of the boom, a door for said bucket, and means to positively operate the door from the boom to open and close the same including a member which travels both along the boom and in contact therewith during door opening and closing operations.

2. In combination, a boom, a bucket to traverse said boom, means to move the bucket outwardly and inwardly of the boom, a door for said bucket, and means to operate the door from the boom including a member

which travels on the boom during door opening and closing operations and means for interrupting such travel during periods when the door is not being operated.

3. In combination, a boom, a bucket to 70 traverse said boom, means to move the bucket outwardly and inwardly of the boom, a door for said bucket, and means to operate the door from the boom including a member which travels on the boom when the door is 75 operated, mechanism operatively connecting said member to the door, and means cooperating with the boom to initiate such travel for both opening and closing operations.

4. In combination, a boom, a bucket, a carriage therefor to traverse said boom, means to move the bucket outwardly and inwardly of the boom, a door for said bucket, and means to operate the door from the boom including a rotatable member which travels 85 on the boom during opening and closing operations of the door, mechanism operatively connecting said member to the door, means on the boom to initiate one of said movements, and means on the member to 90 initiate the other of said movements.

5. In combination, a boom, a bucket to 95 traverse said boom, means to move the bucket outwardly and inwardly of the boom, a door for said bucket, and means to operate the door from the boom including a friction wheel mounted to travel with the bucket and having peripheral flats interrupting contact with the boom, a crank shaft carrying said wheel and connected to the door, 100 trip means for actuating said shaft to initiate contact of the wheel with the boom to operate the door in one direction, and separate means to shift the wheel to operate the door in the opposite direction.

6. In boom bucket door operating mechanism of the class described, the combination of a bucket and support therefor, a door for said bucket swingingly supported on said bucket, a rotatable actuating member, a 110 yieldable support for said actuating member, means for adjusting said support to dispose the actuating member in cooperative relation to the bucket support, a shaft on which said actuating member is mounted, 115 connections between said shaft and the bucket door, and a trip member connected with the shaft for shifting the actuator from inoperative position to cooperative position with relation to the bucket support.

7. In combination, a boom, a carriage to 120 traverse said boom, a bucket swingingly supported from said carriage, a door for said bucket, operating means for said door comprising a friction wheel disposed adjacent the boom, a crank shaft on which said wheel is mounted, a yieldable support in which said shaft is journaled, connections between said shaft and the bucket door, a trip lever connected to said shaft, a trip arm on the 125

boom with which said trip lever is adapted to cooperate to shift the wheel into cooperation with the boom, said wheel having peripheral interruptions to prevent contact of the wheel with the boom except when it is desired to actuate the bucket door.

5 8. In a concrete paver, a distributing bucket having a discharge opening, a door to open and close the opening, linkage loosely sustaining the door for floating movement approximately in the plane of the opening, and an actuating member resiliently connected to the linkage to insure proper closing of the door.

10 9. In a concrete paver, a distributing bucket having a discharge opening, a door for said opening, means to operate the door, and means to clean the door as it moves relatively to the opening, and including a part intermediate the door and bucket to form 20 a tight closure therebetween when the door is closed.

15 10. Mechanism of the class described, comprising, in combination, a receptacle having a discharge opening, a door movable into and 25 out of positions closing said opening, means for mounting said door to allow for said operation, consisting of an arm pivotally mounted on the bucket and pivotally fastened to the door, and a second arm pivoted to the door but having a sliding pin connection with the bucket.

30 11. Mechanism of the class described, comprising, in combination, a receptacle having a discharge opening, a door movable into and 35 out of positions closing said opening, means for mounting said door to allow for said operation, consisting of an arm pivotally mounted on the bucket and pivotally fastened to the door, a second arm pivoted to 40 the door but having a sliding pin connection with the bucket, and means for operating said connection to said first named arm.

45 12. In combination, a boom, a bucket, a carriage therefor, means to move the bucket and its carriage outwardly and inwardly of the boom, a door for said bucket, a member rotatable in only one direction for both opening and closing the door, and mechanism 50 operatively connecting said member to the door.

In testimony whereof I affix my signature.
GEORGE E. WEBB.
